CIRCUIT CONTROLLER

Richard B. Hunter, Shorewood, Wis., assignor to
Cutler-Hammer, Inc., Milwaukee, Wis., a corporation of Delaware

Application June 22, 1939, Serial No. 280,448

19 Claims. (Cl. 175—312)

This invention relates to improvements in systems of circuit control.

The invention relates more particularly to illumination control systems and primarily to systems comprising a plurality of lamp circuits which provide for presetting a plurality of intensities of illumination of each circuit and effecting transition from one preset intensity to another at selective rates which may differ from each other for different circuits.

An object of the invention is to provide a simple system of the aforementioned character which is equally applicable to any of a variety of voltage control apparatus for the lamp circuits.

Another object is to provide a system which may employ resistor or reactor type potentiometers for the pilot or sender circuits.

Another object is to provide a system including individual circuit and master controls whereby transition of the intensity of illumination of an individual circuit from one preset value to another upon transfer from one master circuit to another is effected gradually and continuously.

Another object is to provide a system wherein the aforesaid transition may be made at different selected rates for different lamp circuits.

Another object is to provide a remote control system of the aforementioned nature in which a control current between the sender and receiver flows only during changes of the illumination intensity.

Another object is to provide an illumination control system including a plurality of preset master controllers combined with a single selector and individual intensity control means.

Other objects will hereinafter appear.

An illumination control system of the aforementioned character generally comprises a number of individual lamp circuits, each controllable selectively by a plurality of presettable pilot control devices such as rheostats or the like. The pilot rheostats may be operated either directly to control the brilliancy of the individual lamp circuits or they may be in turn under the control of a plurality of presettable master control rheostats which may be operated selectively to provide for joint control of a selected group of lamp circuits at proportionally varying intensities whereby the ratios of the intensities of the various lamp groups are determined by the setting of the individual pilot rheostats.

The accompanying drawing is a diagram of a system incorporating the present invention. The system comprises two groups of lamps 1 and 2, respectively. Energy is supplied to the

lamps and to the control circuits from the alternating current bus bars L¹ and L². The current for the lamps 1 is supplied through an auto-transformer dimmer 3 which has its primary winding connected across the lines L¹, L² and which is provided with a sliding contact 4 by means of which a variable secondary voltage of the transformer may be impressed on the lamps. The brush 4 connects the various taps of the transformer winding with a contact bar 5 to which one terminal of the lamp circuit is connected, while the other terminal of the lamp circuit is connected to the line L². The brush 4 may be moved along the transformer taps and bar 5 by a screw 6 which is driven by a motor 7, provided with reversing windings, and which motor is controlled by a relay 8.

The relay comprises a lever 8^a, pivoted at its center and provided at each end with a magnet core 8^b and is normally biased to a center position in any suitable manner. The cores are surrounded by polarizing coils 8^c which are connected across the lines L¹, L² in such a manner that the polarity of both cores is in the same direction. A second set of coils 8^d is arranged on the cores 8^b but wound in opposite direction relative to each other so that a current flowing therein unbalances the pull on the two cores to cause rotation of the armature in one or the other direction, depending upon the direction of the current in the coils 8^d. The lever 8^a is provided with a contact arm 8^e which when the lever rotates makes contact with stationary contacts 8^f and 8^g, respectively, to thereby energize one or the other of the reversing windings of the motor 7 and cause the latter to rotate in a corresponding direction.

The circuit arrangement for the lamps 2 and any other additional like circuits is the same as that thus far described for the lamps 1.

The system further includes two fader control units 11 and 12, the unit 11 comprising two potentiometer rheostats or auto-transformers 11^a and 11^b each connected across the lines L¹ and L² and provided with sliding contacts or brushes 11^c and 11^d, respectively. The two brushes 11^c and 11^d are connected with each other mechanically to move simultaneously in opposite directions relative to the lines L¹ and L²; that is, when one of the brushes moves, for instance, in the direction from line L¹ to line L² the other brush moves in the reverse direction. The fader 12 has two similar potentiometers 12^a and 12^b provided with brushes 12^c and 12^d, respectively. They are connected and are operable in a man-

ner similar to that described for the fader unit 11.

There are provided four master potentiometers or auto-transformers 13^a and 13^b and 14^a and 14^b respectively, which are connected between the line L¹ and the terminals 11^d, 12^c, 11^c and 12^d respectively. Potentiometers 13^a and 13^b are provided with sliding contacts 13^c and 13^d, respectively, and potentiometers 14^a and 14^b are provided with similar sliding contacts 14^c and 14^d, respectively.

Each lamp circuit is provided for each scene with two variable rheostats 15^a, 15^b and 16^a, 16^b, respectively. One terminal of each of said rheostats is connected to line L¹, while the other terminal of each is connected to the brushes 13^c, 13^d, 14^c and 14^d, respectively. Sliding contacts 15^c and 16^c which may be moved to various points of the respective rheostats cooperate with the rheostats 15^a, 15^b and 16^a, 16^b, respectively. The primary winding of a transformer 17 is connected between line L¹ and brush 15^c and the primary winding of a transformer 18 is similarly connected between line L¹ and brush 16^c. The secondary windings of the transformers 17 and 18 are connected in series with each other and with the coils 8^d in a circuit between the line L¹ and a bus bar 19. A potentiometer rheostat 20^a is connected across the lines L¹ and L² and is provided with a sliding contact 20^b which completes a circuit between a variable point of the rheostat 20^a and the bus bar 19. The contact 20^b is driven synchronously with the contact 4 and thus the variable voltage impressed by the potentiometer 20^a upon the circuit containing the transformers 17 and 18 and the coils 8^d is a measure of the lamp voltage and brilliancy. The connection is such that the potentiometer voltage is equal and opposite to the transformer voltage when the lamp voltage is equal to the desired amount determined by the setting of the controller. In this case no current flows through the coils 8^d; while the current therethrough when flowing is in one or the other direction relative to the current in coils 8^b, depending upon whether the lamp voltage is lower or higher than the desired voltage.

Scene presetting controllers similar to that aforedescribed for lamp circuit 1 are provided for lamp circuit 2 as shown in the drawing and may obviously be provided for any additional number 50 of lamp circuits desired.

With the system connected and the various control elements adjusted as shown in the drawing, the brush 11^c of potentiometer 11^a has the potential of line L², the brush 11^d of potentiometer 11^b has the potential of line L¹, the brush 12^a of potentiometer 12^a has the potential of line L¹, and the brush 12^d of potentiometer 12^b has the potential of line L². As a result no voltage is impressed on either of potentiometers 13^a or 13^b, and full line voltage is impressed on both of the potentiometers 14^a and 14^b. Therefore no voltage is impressed on potentiometers 15^a and 15^b, but a fraction of the line voltage is impressed on both potentiometers 16^a and 16^b, the voltage of each depending upon the position of the brushes 14^c and 14^d, respectively. The primary winding of transformer 17 therefore has no voltage impressed on it, while a voltage is impressed on the primary winding of transformer 18, this voltage being a fraction of the voltage of the total voltage impressed on the potentiometer 16^b, and depends upon the adjustment of the brush 16^c. The corresponding secondary voltage of transformer 18 is opposed by the voltage of potentiometer 20^a and if a difference exists, the resulting current in

the coils 8^d actuates the relay 8 which in turn controls motor 7 in the manner aforescribed until the two voltages balance, that is until brush 20^b has moved to a point where the lamp voltage has the desired value, when the current in coils 8^d becomes zero and the motor is disconnected.

If now it is desired to change the illumination from scene 2 to scene 1, the brushes 13^c and 13^d of scene potentiometers 13^a and 13^b and the brush 15^c and the corresponding brushes for the other groups of lamps are set to the desired point and at the proper moment the fader potentiometers 11 and/or 12 are moved at the desired rate from the positions thereof shown to their other extreme positions, respectively. This gradually impresses line potential on potentiometers 13^a and 13^b and short circuits potentiometers 14^a and 14^b, so that the various lamp group intensities vary gradually from one value to the new preset value. By operating the brushes 11^c, 11^d and 12^c, 20^d of potentiometers 11 and 12, respectively, at different rates and moving the various brushes 15^c and 16^c in the upper or lower scene lamp potentiometers of the respective pairs to the proper points, it is possible to simultaneously provide 25 for two fading rates for different selected lamp groups.

As no current flows in the circuit between the lamp rheostats and the receiver relay 8 when the desired illumination intensity has been attained, the circuits may then be opened, or alternatively, as there is a certain inertia in the motor and thus a time lag of response, it is possible after attainment of the desired illumination intensity to quickly move the brushes 15^c and/or 16^c from their respective positions on one of the respective pairs of lamp potentiometers to points of equal potential on the other potentiometers of such pairs without a resulting flicker or change in illumination intensity of the lamps. This is of 40 value if it is desired after enactment of a scene to transfer a lamp circuit for control from the quick acting fader to the slow acting fader and vice versa.

It is obvious that the system may be arranged for more than two master faders and also for a greater number of scene master and group controllers to permit the presetting of a greater number of scenes. Other modifications within the scope of the present invention will suggest themselves readily to those skilled in the art.

What I claim as new and desire to secure by Letters Patent is:

1. A control system comprising, a circuit to be controlled, means for presetting a plurality of operating values for an electrical condition of said circuit, comprising, a plurality of transformers having primary and secondary windings, said secondary windings being connected in series relation to each other, a plurality of selectively operative voltage regulators for each of said primary windings, each voltage regulator affording a variable ratio between its input and its output voltages, selective means to impress the output voltage of one of said regulators upon the respective primary winding, and means for increasing the input voltage of one and simultaneously decreasing the input voltage of another of said voltage regulators selectively.

2. A control system comprising a circuit to be controlled, means for presetting a plurality of operating values for an electrical condition of said circuit, comprising, a plurality of transformers having primary and secondary windings, said secondary windings being connected

- in series relation to each other, a plurality of selectively operative potentiometers for each of said primary windings, selective means to vary the output voltage of one of said potentiometers and to impress it upon the respective primary winding, and means for increasing the input voltage of one and simultaneously decreasing the input voltage of another of said potentiometers. 5
10. A control system comprising a circuit to be controlled, means for presetting a plurality of operating values for an electrical condition of said circuit, comprising, a plurality of transformers having primary and secondary windings, said secondary windings being connected in series relation to each other, a plurality of selectively operative potentiometers for each of said primary windings, selective means to vary the output voltage of one of said potentiometers and to impress it upon the respective primary winding, and a plurality of fader potentiometers each arranged to supply a variable voltage to one of said first plurality of potentiometers and to increase the input voltage of one and to simultaneously decrease the input voltage of another thereof. 15
4. A control system comprising a circuit to be controlled, means for presetting a plurality of operating values for an electrical condition of said circuit comprising, a plurality of transformers having primary and secondary windings, said secondary windings being connected in series relation to each other, a plurality of selectively operative voltage regulators for each of said primary windings, each voltage regulator affording a variable ratio between its input and output voltages, selective means to vary the output voltage of one of said regulators and to impress it upon the respective primary winding, and a second plurality of voltage regulators, one for each one of said first plurality of regulators and also affording a variable ratio of their input and output voltages and adapted to cooperate with said first plurality of regulators to impress their respective output voltages thereon. 20
5. A control system comprising a circuit to be controlled, means for presetting a plurality of operating values for an electrical condition of said circuit, comprising, a plurality of transformers having primary and secondary windings, said secondary windings being connected in series relation to each other, a plurality of selectively operative potentiometers for each of said primary windings, selective means to vary the output voltage of one of said potentiometers and to impress it upon the respective primary winding, and a second plurality of variable potentiometers, one for each of said first plurality of potentiometers and adapted to cooperate therewith and to impress their respective output voltages thereon, and a plurality of fader potentiometers, each arranged to supply a variable voltage to one of said second plurality of potentiometers and to increase the input voltage of one and simultaneously decrease the input voltage of another of said second plurality of potentiometers. 25
8. A control system comprising a circuit to be controlled, means for presetting a plurality of operating values for an electrical condition of said circuit comprising, a plurality of transformers having primary and secondary windings, said secondary windings being connected in series relation to each other, a plurality of selectively operative potentiometers for each of said primary windings, selective means to vary the output voltage of one of said potentiometers and to impress it upon the respective primary winding, a second plurality of variable potentiometers, one for each of said first plurality of potentiometers and adapted to cooperate therewith and to impress their respective output voltages thereon, and a plurality of fader potentiometers, each arranged to supply a variable voltage to one of said second plurality of potentiometers and to increase the input voltage of one and simultaneously decrease the input voltage of another of said second plurality of potentiometers. 30
9. A control system comprising a circuit to be controlled, means for presetting a plurality of operating values for an electrical condition of said circuit comprising, a plurality of voltage regulators, common means for selecting one of said voltage regulators and for varying its output voltage and impressing it upon said circuit, and a second plurality of voltage regulators, each of the latter being coordinated with one of each of said first plurality of regulators and also affording a variable ratio of their input and output voltages and adapted to cooperate with said first plurality of regulators to impress their respective output voltages upon the respectively corresponding regulators of said first plurality of regulators. 35
10. A control system comprising a circuit to be controlled, means for presetting a plurality of operating values for an electrical condition of said circuit comprising, a plurality of potentiometers, common means for selecting one of said potentiometers and for varying its output voltage and impressing it upon said circuit, and a second plurality of variable potentiometers, each of the latter being coordinated with one of each of said first plurality of potentiometers and adapted to impress their variable output voltages upon the respective potentiometers of said first plurality. 40
11. In an illumination control system affording individual and joint control of the intensity of a 45

- plurality of groups of lamps for the enactment of a plurality of scenes of illumination, comprising for each group of lamps, a transformer for each of said scenes, said transformer having a primary and a secondary winding, said several secondary windings for each lamp group being connected in series relation to each other, a scene group voltage regulator for each of the several primary windings affording a variable ratio between its input voltage and its output voltage and being adapted to impress the latter upon said primary winding, and a scene master voltage regulator for each of said scenes coordinated with the several respective scene group voltage regulators to impress a variable voltage upon the latter.
12. In an illumination control system affording individual and joint control of the intensity of a plurality of groups of lamps for the enactment of a plurality of scenes of illumination, comprising for each group of lamps, a transformer for each of said scenes, said transformer having a primary and a secondary winding, said several secondary windings for each lamp group being connected in series relation to each other, a scene group voltage regulator for each of the several primary windings affording a variable ratio between its input voltage and its output voltage and being adapted to impress the latter upon the respective primary winding, a scene master voltage regulator for each of said scenes coordinated with the several respective scene group voltage regulators to impress a variable voltage upon the latter, and means for increasing the voltage impressed upon one and simultaneously decreasing the voltage impressed upon another of said master voltage regulators selectively.
13. In an illumination control system affording individual and joint control of the intensity of a plurality of groups of lamps for the enactment of a plurality of scenes of illumination, comprising for each group of lamps individual intensity control means, a plurality of selectively operative voltage regulators affording a variable ratio between their respective input and output voltages, common means to select one of said regulators and to vary its output voltage and impress it upon said intensity control means, and a second plurality of voltage regulators, each of the latter being coordinated with one of each of said first plurality of regulators and also affording a variable ratio of their input and output voltages and adapted to cooperate with said first plurality of regulators to impress their respective output voltages thereon.
14. An illumination control system affording individual and joint control of the intensities of a plurality of groups of lamps for the enactment of a plurality of scenes of illumination, comprising for each group of lamps, individual intensity control means, a plurality of potentiometers, common means for selecting one of said potentiometers and for varying its output voltage and impressing it upon said intensity control means, and a second plurality of variable potentiometers, each of the latter being coordinated with one of each of said first plurality of potentiometers and adapted to impress their variable output voltages upon the respective potentiometers of said first plurality.
15. An illumination control system adapted to provide for individual and/or joint control of the intensities of illumination of a plurality of groups of lamps for the enactment of a plurality of scenes sequentially, comprising intensity control means individual to each group of lamps, each of said control means comprising a plurality of pairs of potentiometers, means common to each pair of potentiometers for presetting one of the same for preselecting the output voltage thereof when rendered active whereby said output voltage is impressed upon said intensity control means, a second plurality of pairs of potentiometers, means individual to each potentiometer of said last mentioned pairs for preselecting the respective output voltages thereof, said last mentioned pair of potentiometers being electrically connected with the first mentioned pairs of potentiometers to provide for impressing the respective output voltages of the former, when rendered active, upon the latter, a plurality of pairs of fader potentiometers, each pair of fader potentiometers having a pair of jointly movable contactors associated therewith, each pair of contactors in one extreme position thereof being respectively adapted to render active and inactive one potentiometer of each of said second mentioned pairs, thereby tending to render active or inactive the corresponding potentiometers of said pairs first mentioned to provide for enactment of an illumination effect of said groups of lamps jointly for a given scene, and each pair of contactors in the other extreme position thereof providing for a reversal of the conditions last mentioned.
16. An illumination control system adapted to provide for individual and/or joint control of the intensities of illumination of a plurality of groups of lamps for the enactment of a plurality of scenes sequentially, comprising intensity control means individual to each group of lamps, each of said control means comprising a plurality of pairs of potentiometers, means common to each pair of potentiometers for presetting one of the same preselecting the output voltage thereof when rendered active whereby said output voltage is impressed upon said intensity control means, a second plurality of pairs of potentiometers, means individual to each potentiometer of said second mentioned pairs for preselecting the respective output voltages thereof, said second mentioned pairs of potentiometers being electrically connected with the first mentioned pairs of potentiometers to provide for impressing the respective output voltages of the former, when rendered active, upon the latter, a plurality of pairs of fader potentiometers, each pair of fader potentiometers having a pair of jointly movable contactors associated therewith, each pair of contactors in one extreme position thereof being respectively adapted to render active and inactive one potentiometer of each of said second mentioned pairs, thereby tending to render active or inactive the corresponding potentiometers of said pairs first mentioned to provide for enactment of an illumination effect of said groups of lamps jointly for a given scene, each pair of contactors in the other extreme position thereof providing for a reversal of the conditions last mentioned, said pairs of contactors being normally movable simultaneously in a like direction, and the same being alternatively movable independently of each other at different rates.
17. A control system comprising, a circuit to be controlled, means for presetting a plurality of operating values for an electrical condition of said circuit, comprising, a plurality of fixed ratio transformers having primary and secondary windings, said secondary windings being connect-

ed in series relation to each other, an individual voltage regulator for each of said primary windings and affording a variable ratio between its input and its output voltage, and means for increasing the input voltage of one and simultaneously decreasing the input voltage of another of said voltage regulators.

18. An illumination control system comprising a circuit to be controlled, means for presetting a plurality of operating values for an electrical condition of said circuit comprising, a plurality of pairs of voltage regulators, common means for selecting one voltage regulator of each of said pairs and for varying its output voltage and impressing it upon said circuit, and a second plurality of pairs of voltage regulators, the respective regulators of said last mentioned pairs being individually coordinated with the regulators of said first plurality of pairs and also affording a variable ratio of their input and output voltages and adapted to cooperate with the

selected regulators of said first plurality of pairs of regulators to impress their respective output voltages upon the respectively corresponding regulators of said first plurality of pairs.

19. An illumination control system comprising a circuit to be controlled, means for presetting a plurality of operating values for an electrical condition of said circuit comprising, a plurality of pairs of potentiometers, common means for selecting one potentiometer of each of said pairs and for varying its output voltage and impressing it upon said circuit, and a second plurality of pairs of potentiometers, the respective potentiometers of said last mentioned pairs being individually coordinated with the potentiometers of said first plurality of pairs and respectively adapted to impress their variable output voltages upon the selected potentiometers of said first plurality of pairs.

RICHARD B. HUNTER. 20
